UNITED STATES PATENT OFFICE.

WILLIAM CAMERON, OF CHICAGO, ILLINOIS, ASSIGNOR TO TORRIS WOLD & COMPANY,
OF CHICAGO, ILLINOIS, A CORPORATION OF ILLINOIS.

AUTOMATIC DIE-PRESS.

1,337,307.

Specification of Letters Patent. Patented Apr. 20, 1920.

Original application filed May 25, 1917, Serial No. 170,838. Patent No. 1,277,342, dated August 27, 1918.
Divided and this application filed May 18, 1918. Serial No. 235,961.

To all whom it may concern:

Be it known that I, WILLIAM CAMERON, a citizen of the United States, residing at Chicago, in the county of Cook and State 5 of Illinois, have invented certain new and useful Improvements in Automatic Die-Presses, of which the following is a specification.

This invention, a division of my Patent 10 No. 1,277,342, granted August 27, 1918, for sheet feeding mechanism, relates to automatic die presses, particularly of the type employed for punching out from sheet metal blanks the tops and bottoms of tin cans and 15 other receptacles, the shape of the articles or objects produced by the press being, of course, dependent upon the size and shape of the punches and dies employed in the machine.

20 One of the objects of the invention resides in the provision of a generally improved blank feeding mechanism by which the blanks are advanced intermittently to the dies. It is highly essential that successive blanks being fed to the dies shall not overlap; otherwise, if overlapping portions were pressed between the dies, injury to the dies would result. The liability of overlapping of ends of the succeeding blanks is 25 eliminated by my improved blank feeding mechanism by insuring a slight separation of the ends of successive blanks from each other, regardless of whether the blanks are not all cut exactly even and of the same 30 length, although they might be intended to be of uniform length.

Other features of my improved blank feeding mechanism are the provision of interchangeable feed bars and blank feeding 40 dogs of novel construction, and the provision of improved means for operating the feed bar including a frangible element which will be sheared off in case the feed bar shall catch, or for any reason excessive 45 strain should be imposed thereon.

Other objects and many of the inherent advantages will be readily appreciated by those skilled in the art as the invention becomes better understood by reference to the 50 following description when considered in

connection with the accompanying drawings, in which—

Figure 1 is a front elevation, partially in section, of that portion of a die press embodying my invention;

Fig. 2, an end elevation on a reduced scale looking toward the right at Fig. 1, omitting such parts of the press as are unnecessary for an understanding of my present improvements;

Fig. 3, a fragmentary detail view, showing the manner of adjusting the back bar of the feed channel to accommodate the machine to blanks of various widths, this view being taken substantially on line 3—3 of Fig. 2;

Fig. 4, an enlarged view, partially in section, of certain parts shown in Fig. 2;

Fig. 5, a fragmentary sectional view taken on the line 5—5 of Fig. 4, showing the construction and arrangement of the feeding dogs and one of the sheet clamping members; and

Fig. 6, a plan view of the clamp shown in Fig. 5.

Referring to the drawings, it will be noted that I have limited them to a showing of only such parts of an automatic die press as are necessary for a clear understanding of my present improvements. In a machine 80 of this character, the blanks are successively lifted from a magazine and positioned in operative relation to a feeding device which feeds each blank in step-by-step movements to the dies. The particular construction and 85 operation of the magazine, the blank-lifting means, the dies and the means for operating these instrumentalities in synchronism are not essential to my present improvements, hence they are illustrated in the drawings simply for purpose of clarity. For an understanding of the complete machine, reference may be had to my application mentioned above. It will be sufficient to mention that the sheet metal blanks to be 90 fed to the machine are stacked one upon another in a suitable magazine 12 carried by the frame, which is indicated by character 13. This frame is formed to provide a pair 95 of upstanding supports 14 in which the 100

main power shaft 15 of the machine is journaled. A power pulley or belt wheel 16 rotatably mounted upon one end of the shaft 15 is continuously driven by a belt from any suitable source of power. Any suitable manually controlled clutch may be employed for connecting the power pulley to, and disconnecting it from the shaft, as is well understood in this art. In Fig. 2, is shown the connecting rod 17 of the crank operated by the power pulley for reciprocating the head 18 carrying the movable die. This movable die cooperates with the stationary die 19, (Fig. 1) to cut or punch out objects or articles from sheet metal blanks in the usual manner, which are fed between the dies as described later.

The blanks are lifted or picked up, one at a time, from the magazine by pneumatic lifters of any suitable or preferred construction. It will be sufficient to state that these lifters consist of a plurality of (in the present instance four) sucker heads 21 mounted upon the lower ends of pipes 22, which are mounted to reciprocate in fixed slide bearings 23 and are connected together at their upper ends by a header pipe 24. Each of the sucker heads is slightly cup shaped on its lower surface and provided with an aperture through which suction is exerted upon the uppermost sheet or blank in the magazine when the sucker heads are pressed into engagement with the uppermost blank. The sucker heads are reciprocated between the extreme upper position in which they are shown in Figs. 1 and 2 to their extreme lower position which continually varies with the number of the blanks in the magazine, by suitable mechanism, only partially illustrated and designated by the character 25, operated from the main drive shaft 15. This operating mechanism is so designed that at each actuation of the shaft 15, the sucker heads will travel a variable distance depending upon the height of the stack of sheets in the magazine and will engage and lift the upper sheet into a predetermined position from which it may be transferred to the feeding mechanism.

From the elevated position to which the uppermost blank has been lifted by the sucker heads as shown by the blank indicated by reference character 26, (Fig. 2) the lifted blank is transferred edgewise into an inclined slot or guideway along which it is fed longitudinally to the operating dies. The transferring mechanism may be of any suitable construction, and need only be mentioned here as consisting of a plurality of transmitters 27 adapted to reciprocate parallel with the plane of the blank 26 for moving the blank into the slot or guideway just mentioned. The transmitters are operated by suitable means from the power shaft 15 in synchronism with the pneumatic lifters

and the feeding mechanism which will be presently described.

The depth to which the blank 26 will enter the slot or guideway is determined by a back bar 28 adjustably mounted in the bottom of the feed slot and provided with rearwardly disposed tapped bosses 29 adapted to receive adjusting screws 31 by means of which the height of the back bar may be manually adjusted and regulated. This construction will be readily apparent from Figs. 3 and 4, from which it will be seen that if narrow blanks are to be operated upon the back bar will be adjusted upwardly so that when the lower edge of a blank is resting on the back bar the blank will be in proper longitudinal alignment with the operating dies. If wider blanks are employed the back bar will be adjusted downwardly the requisite amount, and it should be manifest that by means of the adjusting screws disclosed the back bar may be adjusted and regulated to a fine degree of nicety.

After being transferred into the feed slot in the manner previously explained the blank is fed forwardly to the dies in a step-by-step movement by means of feeding mechanism, which will now be described. On the lower side of the feed slot the frame is formed to provide an elongated recess 95 or guideway 32 shaped to accommodate a reciprocatory feed bar 33, Figs. 4 and 5. This feed bar is of substantially L-shape in cross section and is provided with a series of spaced pivot pins 34 threaded into or otherwise fixedly secured to the upwardly extending portion of the feed bar and projecting outwardly substantially flush with the opposite face of the bar. These pins are spaced apart a distance equal to the desired forward movement of a metal blank at each actuation so that the blank will be positioned between the dies between successive operations of the dies. The feed bar is reciprocated a uniform distance at each stroke by mechanism which will be later described and if a longer or shorter travel of the blanks is desired to conform to larger or smaller objects to be punched out from the blank at each operation of the dies, the feed bar is withdrawn longitudinally from its guideway and is replaced by a feed bar on which the pins 34 are spaced a greater or less distance apart in accordance with the requirements of the dies.

Upon each pin 34 there is pivotally mounted a feed dog 35 which is simply slipped onto the pin, where it is held when the feed bar is in operative position by the upper side wall of the feed bar guideway. Each feed dog is capable of a limited pivotal movement on its pin, and when disposed beneath a blank 26 the dog assumes the position in which the central dog is shown in Fig. 5. When upon reciprocatory movement

of the feed bar a dog is withdrawn from beneath the blank it is elevated so as to engage behind the rear edge of the blank as shown at the left in Fig. 5, this movement being effected by a small expansion spring 36 disposed in a socket formed in the dog and pressing at opposite ends against the bottom of the socket and a plunger 37 respectively, which projects from the socket into engagement with the laterally extending portion of the feed bar.

All of the feed dogs are spaced apart the same distance on any particular bar and all of the dogs are of the same length with the exception of the two end dogs. It is highly essential that successive blanks being fed to the dies shall not overlap or otherwise, if overlapping portions were presented between the dies, injury to the dies would result. Since the blanks are not all cut exactly evenly and of the same length, even if they were intended to be of uniform length, I have found it desirable to insure a slight separation of the ends of successive blanks from each other. To accomplish this purpose I make the first dog at the left hand end of the feed bar, which imparts the initial feeding stroke to the blank, a little shorter than the other dogs so that the first feeding step of the blank will not cause the forward end of the new blank to overlap the rear end of the next preceding blank. The result is that even if the new blank is a little longer than the standard length employed, the first stroke upon the blank will be a little shorter than the succeeding strokes, so that all liability of overlapping of the ends of succeeding blanks is eliminated. It should also be understood that the feed dogs are readily removable and interchangeable so that if short blanks are to be operated upon the short dog, which is normally at the extreme left hand end of the feed bar, is moved to the right a distance determined by the decrease in length of the blanks to be operated upon, so that the shorter dog is always employed to impart an initial feeding stroke to a blank.

The feed bar is reciprocated to feed the blanks forward intermittently by mechanism driven from the main shaft 15 so that at each revolution of this shaft a complete stroke of the feed bar is performed. Referring now to Figs. 1 and 2, it will be observed that upon a laterally projecting bracket 38 I have mounted a bell crank lever 39 which is oscillated by means of a link 41 connected at its lower end to one of the arms of the bell crank lever and at its upper end to a crank pin 42 carried by the end of the shaft 15. The other arm of the bell crank lever 39 is connected by a link 43 with a bifurcated releasing member 44 permanently pivoted by a pin 45 to a slide block 46 which travels upon suitable guide-

ways 47 fixed to the main frame of the machine. In order to obviate injury to the machine in case the feed bar should become stuck for any reason whatsoever, the release member 44 is connected with the slide member 46 with a frangible pin 48. It will be obvious, therefore, that if upon feeding movement toward the right, viewing Fig. 1, the feed bar should catch or excessive strain should be imposed thereon, the frangible pin 48 would be sheared off, permitting the release member 44 to swing downwardly on its pivot pin 45. The machine will then continue to run and the release member will be swung back and forth idly on its pivot 45 until the machine is stopped, the difficulty is remedied, and a new frangible pin 48 is inserted.

The feed bar is connected with the slide member 46 by a spring bolt or pin 49 which is carried by the slide member 46 and yielding projected upwardly above the member by an expansion spring 51 into an aperture designed to receive the pin and formed in the outer end of the feed bar. Whenever it is desirable to replace one of these feed bars by another it is only necessary to depress the pin 49 out of engagement with the feed bar, whereupon the bar can be withdrawn longitudinally from its guideway.

For the purpose of preventing return movement of the blanks in the feed slot with the feed bars I have provided a series of yielding holding devices each consisting, as shown in Fig. 4, of a spring-pressed pin 52 projecting upwardly from the lower face of the feed slot into engagement with a blank in the slot, and these pins, urging the blank against the opposed face of the feed slot formed by a member 53 shaped as shown in Fig. 4, serve to yieldingly clamp the blank so as to prevent any retrograde movement thereof.

For the purpose of securely holding the blank adjacent to the dies and particularly for the purpose of holding the rear end of a blank during the last operation on the blank I have provided a pair of clamping members located at the delivery end of the feed slot and in proximity to the dies, which serve to firmly clamp and hold the feed blank in the requisite position during the operation of the dies. These clamps, only one of which is shown in Figs. 1, 5 and 6, each comprise a stationary member 54 provided with a downwardly curved shoe 55 over which the blank travels and by which it is supported, and a movable clamping member 56 adapted to coöperate with said shoe to clamp and hold the blank. The member 54 is secured so as to be capable of longitudinal adjustment to a vertical web 57 of a bracket 58 which is in turn adjustably mounted for lateral adjustment upon a stationary bar 59. The bracket is secured

to the bar by a bolt 61 passing through a slot in the bracket, and the member 54 is secured to the vertical web of the bracket by a bolt 62 extending through a horizontal slot 5 in the web. The adjustability provided by these slotted mountings permits the brackets to be adjusted toward and from each other to accommodate the clamps to blanks of various widths and also permits the clamps 10 to be adjusted toward and from the dies. The clamping member 56 is pivoted to the stationary member 54 upon a pivot pin 63 and is yieldingly depressed so that its down-turned end is urged toward the shoe 55 by 15 an expansion spring 64 interposed between the top of the clamping member and an adjustable nut 65 threaded upon an upwardly projecting bolt 66 which is anchored in the base of the bracket 58 and passes loosely 20 upwardly through the clamping member. It will be apparent from Fig. 5 that as a blank is fed forward it passes between the shoes 55 and the clamping member 56 by which it is firmly clamped and held in 25 requisite position with respect to the dies.

My invention and its mode of operation should be understood from the foregoing without further description, and it should be obvious that the various structural details shown and described should be capable of considerable modification and variation within the scope of the appended 30 claims.

I claim:

35 1. In a machine of the character described, the combination of a reciprocatory feeding bar, a reciprocatory slide member, a disengageable spring pin connection between said feeding bar and said slide member adapted for manual release only, and means for reciprocating said slide member including a connection adapted to be released when excessive strain is imposed thereon.

45 2. In a machine of the character described, the combination of a reciprocatory slide member, mechanism for operating the same comprising a member pivoted to said slide member at one point and releasably 50 connected thereto at another point, and a plurality of feed dogs carried by said slide member.

3. In a machine of the character described, the combination of a frame provided with a feed bar guideway, a feed bar reciprocable therein, a series of pins mounted on and projecting laterally from said bar, and a plurality of dogs removably mounted on said pins, said guideway including means for retaining said dogs in position on said pins when said feed bar is disposed in the guideway.

4. In a machine of the character described, the combination of a frame provided with a feed bar guideway, a feed bar

adapted to reciprocate therein, a plurality of pins fixedly carried by said feed bar in uniformly spaced relation, and a dog removably disposed upon each pin, said dogs being of varying lengths and interchangeable upon withdrawal of said bar from said guideway.

5. In a machine of the character described, the combination of a reciprocatory feed bar, and means carried by said feed bar for advancing blanks, said means comprising a plurality of dogs of different lengths arranged to advance a blank a uniform distance at each actuation of the feed bar except upon the initial or final movements of said blank.

6. In a machine of the character described, the combination of means for feeding blanks to a tool, a member projecting longitudinally at one side of the path of travel of the blanks and provided with a laterally projecting horizontal guide portion over which the blanks travel toward the tool, and means carried by said member and constantly urged at its free end toward said guide portion to clamp and hold the blank between each successive feeding operation.

7. In a machine of the character described, the combination of means for feeding blanks and blank-holding means arranged between said feeding means and a tool, said blank-holding means comprising an adjustably mounted normally stationary member provided with a guide, a member pivotally connected to said stationary member, and means for yieldingly urging said pivotal member toward said guide to yieldingly clamp a blank.

8. In a machine of the character described, the combination of a reciprocatory feed bar, a series of pins fixedly mounted on said bar in uniformly spaced relation, a dog pivotally mounted upon each of said pins and freely removable therefrom upon withdrawal of said bar from the machine, said dogs being of various lengths and interchangeable, and means for reciprocating said bar a uniform distance at each reciprocation, the distance that a blank would be advanced at each reciprocation being determined by the length of the particular dog engaging said blank.

9. In a machine of the character described, the combination of a reciprocatory feed bar for advancing blanks in a step by step movement, a sliding member detachably connected to said feed bar, a link for reciprocating said slide member, and a connection between said link and slide member, including a swinging member pivoted at one end to the slide member and at its other end to said link and also releasably connected at said other end to said slide member so that under excessive strains said link

will be caused to swing upon its pivotal connection with said slide member so as to permit the feeding movement of said feed bar to be interrupted.

- 5 10. In a machine of the character described, the combination of a reciprocatory member, a swinging link pivoted at one end to said member and releasably connected remote from said pivotal point to said member, and an operating member connected to said swinging link at a point spaced from said reciprocatory member so that under excessive strain said releasable connection will permit said swinging link to swing about its pivot.
- 10 11. In a machine of the character described, the combination of a reciprocatory member, a reciprocating member, and a connection between said members comprising

ing a swinging link pivoted at opposite ends to said members and a releasable connection between said swinging link and one of said members, said three connections being out of line with respect to each other so that under excessive strain said releasable connection will permit a continued movement of said reciprocating member without movement of said reciprocatory member.

12. In a machine of the character described, the combination of a reciprocatory feed bar for advancing blanks in step-by-step movements, and means for reciprocating the feed bar comprising a reciprocatory member and a link permanently pivoted to the feed bar at one point and releasably connected to the feed bar at another point.

WILLIAM CAMERON
